COIN PURSE

Nels H. Swanson, Chicago, Ill.

Application March 29, 1941, Serial No. 385,805

2 Claims. (CL 150—35)

This invention relates to a special type of coin purse in which a rack for the coins is mounted between covers within which it is normally enclosed, and in which the covers are preferably made of flexible material, such as leather.

One object of the invention is to provide a structure of the type indicated in which the coin rack is firmly anchored to the cover material in a manner which causes the rack to stand upright away from the cover when the purse is opened.

Another object is to provide a construction which shall be convenient and economical to manufacture, and which includes certain features insuring speed and accuracy in the assembly of the parts.

The invention is also concerned with providing certain methods of assembly which insure a simple and durable construction.

Other objects and advantages of the invention will appear as the description proceeds.

In the drawings:

Figure 1 is a perspective view showing in closed position a coin purse embodying this invention.

Figure 2 is a perspective view showing the coin purse in open position and with the coins removed therefrom.

Figure 3 is a plan view of the cover and lining assembled with the "hookless fastener" element ready for stitching.

Figure 4 is a similar plan view showing the cover and lining after stitching.

Figure 5 is a vertical sectional view taken through the back of the cover and through the coin rack showing the method of assembling these parts.

Figure 6 is an enlarged detail section of the riveting means at the moment of clinching a rivet in assembling the parts.

In the coin purse to which this invention is directed the cover, which is made of flexible sheet material, such as leather, comprises two leaves 1 and 2 extending in opposite directions from a back portion 3 which is integral with the two leaves and extends transversely of them in the closed position of the purse, as illustrated in Figure 1. For holding the two leaves together a "hookless fastener," commonly called a "zipper," is shown at 4, with the tape portions 5, 5 of the fastener extending from the margins of the cover leaves 1 and 2 and completing the end and side walls of the purse in its closed position.

The inner face of the cover member is preferably provided with a lining 6 of sheet material which may be of a single piece covering the leaves 1 and 2 and the back section 3. The lining will

be secured to the cover member at its margins and may be formed with slits 7 and 8 to provide pockets for carrying paper money, cards or other flat material. The coin rack itself includes a back bar 9 formed of sheet metal with marginal flanges 10, and with upstanding channel members 11 each having a base or foot flange 12 by which it is secured to the back bar 9 between the flanges 10 thereof. The channels of the members 11 face each other in pairs to form guideways for the coins carried in the purse. The back bar 9 is perforated at intervals, and the foot flange 12 of each channel member is formed with an aperture so that these members may be secured 15 to the back bar by rivets.

In assembling the various parts of the coin purse I have found it both convenient and desirable to secure the coin rack in the cover by means of some of the rivets which are employed for holding the channel arms 11 of the rack to the back bar. With this method of assembly in view, the cover member is initially made with a series of perforations 13 in the area which is to form the back portion 3 of the cover, and these 20 perforations are spaced so as to register accurately with certain holes in the back bar 9. Additional perforations 13 are formed in the corresponding area of the lining member 6. Thus, for assembling the cover and lining a very simple jig 25 may be provided having a pair of upstanding pins or posts 14 spaced apart to fit into two of the perforations 13 so that the cover and its lining may be fitted onto these pins 14 and will then be disposed in correct relation to each other. Any suitable cement is applied to the marginal portion 30 of the inner face of the cover and to the opposing marginal area of the lining indicated in Figure 3 at 6a, and the tape portions 5 of the "hookless fastener" are inserted between these cemented 35 marginal areas for securement between them. Pressure is applied and the cement is given time to "set" or dry to the desired extent; then the assembled cover, lining and fastener elements are removed from the guide pins 14 and 40 further secured by marginal stitching, indicated at 15 in Figure 4. Although the fastener tapes 5 are necessarily curved to some extent to form the ends and side walls of the purse, they are 45 comparatively flexible and do not interfere with the stitching operation during which the cover, as a whole, lies substantially flat, as shown in 50 Figure 4.

It is not necessary that all the rivets which secure the channeled members 11 to the back bar 9 shall extend through the cover, and therefore

I prefer to initially assemble the back bar 9 with two pairs of members 11, one pair at each end, as seen in Figure 5. The riveting machine includes an upstanding hollow anvil post 16 within which there is a plunger 17 normally upheld by a spring 18 and having a reduced terminal pin 19 extending above the upper end of the anvil post 16. The apertured foot flange 12 of one of the channeled members 11 is first fitted over the pin 19 and the corresponding aperture of the back bar 9 is next entered over the pin 19. Then the assembled cover and lining is inverted over the back bar and the proper perforation 13 is engaged with the pin 19 to correctly position the cover with respect to the back bar 9. The riveting plunger 20 to which a rivet 21 is automatically fed by suitable mechanism, not shown, is then depressed, carrying the rivet 21 into contact with the upper end of the pin 19 and depressing the pin and its connected plunger 17 in opposition to the spring 18 so as to carry the shank of the rivet through the back portion 3 of the cover and through the lining 6 and through the apertures in the back wall 9 and foot flange 12. As seen in Figure 6, the rivet is of the hollow shank type, and the upper end of the pin 19 is formed with a convex terminal portion 19a. The spring 18 is sufficiently stiff to insure that the pressure between the convex terminal 19a and the hollow end of the rivet will serve to spread the annular edge of the rivet so that as the pin 19 descends within the anvil post 16 this edge will be curled back by contact with the annular channel 16a in the upper end of the post 16 for clinching against the foot flange 12 and thus securing the parts in assembled relation. As shown in the drawings, the perforations 13 of the cover and lining correspond to the middle four apertures in the back bar 11, so that the four channel members 11 which form the racks for the two middle groups of coins are assembled in the process of securing the rack into the cover, and the corresponding four rivets 21 extend through the back 3 of the cover, as seen in Figure 1. The setting of these rivets completes the assembly and secures the back bar firmly and flatly to the back portion 3 so that when the cover is opened up in flat form, as in Figure 2, the coin rack stands away from the leaves of the cover, thus presenting the coins (not shown) in conveniently accessible position. The utilization of the holes 13 for aligning the cover and its lining on the guide pins 14 insures accurate assembly of these parts, and with the holes 13 formed initially in the blanks of the cover and lining by the same dies which cut the outlines of these parts, the correct positioning of the coin rack in the cover is insured at the outset. The securing of the rack by means of the rivets permits the stitching of the lining to the cover to be carried out with the parts in flat form, and without the interference which would be offered by the rack if it were installed at an earlier stage in the

assembly. The structure and method of combining the elements in accordance with this invention thus insures economical manufacture and a satisfactory final product.

A further advantage which results from the use of the rivets 21 in the back portion 3 of the cover is that the pockets formed between the cover and the lining at the slits 7 and 8 are thus separated from each other without the necessity of running the stitching across the cover, as would otherwise be necessary; the rivets 21, in cooperation with the rigid back bar 9, serve to bind the cover and lining together so closely that there is no possibility that articles in one pocket will tend to slip through toward the other pocket or to extend part way through, where they would interfere with the closing of the cover leaves.

While there is shown and described herein certain specific structure embodying the invention, it will be manifest to those skilled in the art that various modifications and re-arrangements of the parts may be made without departing from the spirit and scope of the invention, and that the same is not limited to the particular form herein shown and described, except in so far as indicated by the appended claims.

I claim as my invention:

1. A coin purse comprising a cover of flexible sheet material including a narrow perforated back portion and two foldable leaves extending in opposite directions from the back portion, a lining comprising a single sheet of material secured against the inner face of the cover at its margins only, said lining having a slit to form a pocket between the lining and the cover and having perforations registering with those of the back portion, together with a coin holding frame including a back bar and fastening means extending through the perforations of the cover and lining and securing the back bar thereto whereby the cover and lining are held together to form a bottom for the pocket between them.

2. A coin purse comprising a cover of flexible sheet material including a narrow perforated back portion and two foldable leaves extending in opposite directions from the back portion, a lining comprising a single sheet of material secured against the inner face of the cover at its margins, said lining having a slit to form a pocket between the lining and the cover and having perforations registering with those of the back portion, together with a coin holding frame including a back bar and channeled coin receiving bars each having a foot flange seated upon the back bar, and rivets extending through said foot flanges and back bar and through the perforations of the cover and lining securing the channeled bars to the back bar and clamping the back bar to said cover with the lining interposed, whereby the cover and lining are held together to form a bottom for the pocket between them.

NELS H. SWANSON.
